ABSTRACT: The disclosure embodies a record-processing tool and includes mechanism for activating the tool to punch or detect a code hole in a record medium. The tool is activated by a lever selectively pivoted about one of two opposite-acting fulcrums by cyclically operable means, selection being dependent on the retraction of one of the fulcrums.

RECORD PROCESSING MECHANISM

SUMMARY OF THE INVENTION

The invention resides in the provision of a mechanism which selectively pivots a lever about one of two opposite-acting fulcrums to activate a record-processing tool.

IN THE DRAWINGS

FIG. 1 is a plan view of a record-processing mechanism embodying features of the invention, showing the operating parts of the mechanism in their normal positions;

FIG. 2 is a side view;

FIG. 3 is a plan view of a modification of the record-processing mechanism shown in FIG. 1; and

FIG. 4 is a side view of the modification of FIG. 3.

With reference to FIGS. 1 and 2, the mechanism includes a supporting means 12, a record-processing tool or punch 24, a cyclically operable means 26, and a motion transmitting mechanism 40. The punch 24, the cyclically operable means 26, in the motion-transmitting mechanism 40 may be mounted on a pair of upright plates 14 of supporting means 12, of which only one is shown. The punch 24 in the cyclically operable means 26 are spaced-apart with the motion-transmitting mechanism 40 therebetween.

A rotatable camshaft 42 is journaled on the plates 14 and may be rotated by any one of many well-known business machine motors. The camshaft 42 has a first or drive cam 34 affixed thereon.

The drive cam 34 is an eccentric having a high point 33 and a low point 35. The drive cam 34 is journaled in a link 37 pivotally connected to a rockable lever 22. The punch 24 is pivotally connected to one end 30 of the lever 22, forming a first fulcrum 15 at its point of contact therewith. When the mechanism is in its normal position, the end 30 of the lever 22 is yieldably urged by a coil spring 23 against a first stop member 16, which is affixed to the plates 14; and the other end 32 of the lever 22 rests upon a second stop member 20, which is also affixed to the plates 14.

A bellcrank 19 is pivotally positioned on the plates 14 such that a projection on the bellcrank 19 forms a retractable second fulcrum 21 effective to restrain the end 32 of the lever 22 from pivoting away from the stop member 20 when the bellcrank 19 is rotated toward the lever 22. The bellcrank 19 is biased in this direction by a coil spring 29 but is normally held away by a retractable latch 48, retractable by a power means 28, which may be a solenoid.

A second or reset cam 44 is also affixed to the camshaft 42. The reset cam 44 is an eccentric having a high point 43 and a low point 41. A cam follower roller 27 is attached to one arm of a tripodal lever 25 and is yieldably urged against the reset cam 44 by a coil spring 45. A second arm of the tripodal lever 25 is pivotally mounted to the bellcrank 19 at its point of pivotal connection 17 to the plates 14. A third arm 39 of the tripodal lever 25 extends to position effective to reset the latch 48 to its normal position, supplementing the latch resetting action of the coil spring 46, when the tripodal lever 25 is pivoted clockwise (FIG. 2) toward the latch 48 by the action of the reset cam 44. A stud 31 is affixed to the third arm 39 of the tripodal lever 25 in a position effective to reset the bellcrank 19 to its normal position shown when the tripodal lever 25 is pivoted toward the bellcrank 19 by the action of the reset cam 44.

A shackle 36 is pivotally mounted between the lever 22, at the point of pivotal connection of the link 37 to the lever 22, and the plates 14, at the pivot point 38.

A punch die 47 is secured to the plates 14 with its perforation aligned to the direction of travel of the punch 24.

With reference to FIGS. 3 and 4, the mechanism includes a supporting means 52, a record-processing tool sensing pin 56, a cyclically operable means 76, and a motion-transmitting mechanism 77. The pin 56, the cyclically operable means 76, and the motion-transmitting mechanism 77 may be mounted

on a pair of upright plates 54 of supporting means 52, of which only one is shown. The pin 56 and the cyclically operable means 76 are spaced apart with the motion-transmitting mechanism 77 therebetween.

5 A rotatable camshaft 98 is journaled on the plates 54 and may be rotated by any one of many well-known business machine motors. The camshaft 98 has a first or drive cam 51 affixed thereon.

The drive cam 51 is an eccentric having a high point 55 and 10 a low point 53. The drive cam 51 is journaled in a link 57 pivotally connected to a second rockable lever 72. A first rockable lever 64 is pivotally connected to one end 74 of the second lever 72. When the mechanism is in its normal position, the other end 63 of the second lever 72 rests upon a second stop member 70, which is affixed to the plates 54.

15 The sensing pin 56 is pivotally connected to one end 59 of the first lever 64, the pivotal connection forming a first fulcrum 58, and is yieldably urged by a coil spring 84 against a pin return stop member 64, which is affixed to the plates 54. 20 When the mechanism is in its normal position, this end 59 of the first lever 64 rests upon a first stop member 62, which is affixed to the plates 54; and the other end 61 of the first lever 64 is yieldably urged by a coil spring 82 against a third stop member 60, which is also affixed to the plates 54.

25 A control member 68, which may be a switch, is positioned on the plates 54 such that it will be actuated by the end 61 of the first lever 64 as it pivots away from the third stop member 60. An actuating arm of the control member 68 is yieldably biased against the end 61 of the first lever 64 and forms a 30 movably yieldable second fulcrum 66 at its point of contact therewith.

35 A bellcrank 88 is pivotally positioned on the plates 54 such that a projection on the bellcrank 88 forms a retractable fulcrum 89 effective to restrain the end 63 of the second lever 72 from pivoting away from the second stop member 70 when the bellcrank 88 is rotated toward the second lever 72. The bellcrank 88 is biased in this direction by a coil spring 94 but is normally held away by a retractable latch 90, retractable by 40 power means 80, which may be a solenoid.

45 A second or reset cam 96 is also affixed to the camshaft 98. The reset cam 96 is an eccentric having a high point 95 and a low point 97. A cam follower roller 99 is attached to an arm of a tripodal lever 92 and is yieldably urged against the reset cam 96 by a coil spring 67. A second arm of the tripodal lever 92 is 50 pivotally mounted to the bellcrank 88 at its point of pivotal connection 93 to the plates 54. A third arm 91 of the tripodal lever 92 extends to a position effective to reset the latch 90 to its normal position, supplementing the latch resetting action of the coil spring 87, when the tripodal lever 92 is pivoted toward the latch 90 by the action of the reset cam 96. A stud 83 is 55 affixed to the third arm 91 of the tripodal lever 92 in a position effective to reset the bellcrank 88 to its normal position when the tripodal lever 92 is pivoted toward the bellcrank 88 by the action of the reset cam 96.

60 A shackle 86 is pivotally mounted between the second lever 72, at the point of pivotal connection of the link 57 to the second lever 72, and the plates 54, at the pivot point 81.

65 A perforated backup 69 is secured to the plates 54. Its perforation 71 is aligned to the direction of travel of the pin 56 and elongated in the direction of travel of the record media.

OPERATION

65 With reference to FIGS. 1 and 2, assuming the mechanism, depicted in its normal position, is in an idle mode, the constantly rotating camshaft 42 rotates the drive cam 34 clockwise; and the link 37 is driven upward, as the high point 33 of the drive cam 34 approaches the uppermost point of its travel, exerting an upward force on the lever 22 pivotally connected thereto. The lever 22 is restrained at one end 30 by the coil spring 23, but the other end 32 is free and moves upward, pivoting about the first fulcrum 15. After the high point 33 of the drive cam 34 passes the uppermost point of its travel, the lever 22 is lowered to its normal position.

In a punch mode, the power means 28 is activated, retracting the latch 48. With the latch 48 retracted, the bellcrank 19 will be pivoted toward the end 32 of the lever 22 by the coil spring 29, thus moving the fulcrum 21 into effective position over the end 32 of the lever 22.

The constantly rotating camshaft 42 rotates the drive cam 34 clockwise; and the link 37 is driven upward, as the high point 33 of the drive cam 34 approaches the uppermost point of its travel, exerting an upward force on the lever 22 pivotally connected thereto. The lever is restrained at one end 32 by the retractable fulcrum 21. The other end 30 is forced upward against the bias of the coil spring 23, carrying the punch 24 into agreement with the punch die 47 as the high point 33 of the drive cam 34 reaches the uppermost point of its travel. After the high point 33 of the drive cam 34 passes the uppermost point of its travel, the lever 22 is lowered to its normal position.

The constantly rotating camshaft 42 also rotates the reset cam 44 clockwise. The high point 43 of this cam 44 lags the high point 33 of the drive cam 34 such that it reaches its uppermost point of travel after the high point 33 of the drive cam 34 has passed its uppermost point of travel. The action of the reset cam 44 pivots the tripodal lever 25 clockwise, causing the bellcrank reset stud 31 to pivot the bellcrank 19 clockwise, thus retracting the fulcrum 21 from its effective position relative to the end 32 of the lever 22. The arm 39 of the tripodal lever 25 also supplements the action of the coil spring 46 in restoring the latch 48 to its normal position. By the time the high point 33 of the drive cam 34 reaches its lowermost point of travel, the high point 43 of the reset cam 44 has passed its effective position with respect to the tripodal lever 25; and the bellcrank 19 is once again in its normal position, held away from the end 32 of the lever 22 by the retractable latch 48.

The function of the shackle 36 is to restrict the motion imparted to the lever 22 by the drive cam 34 at the pivotal point of connection of the link 37 to the lever 22 such that this point effectively reciprocates vertically.

With reference to FIGS. 3 and 4, assuming the mechanism, depicted in its normal position, is in an idle mode, the constantly rotating camshaft 98 rotates the drive cam 51 clockwise; and the link 57 is driven upward, as the high point 55 of the drive cam 51 approaches the uppermost point of its travel, exerting an upward force on the second lever 72 pivotally connected thereto. The second lever 72 is restrained at one end by the weight of the first lever 64 pivotally connected thereto, but the other end 63 is free and moves upward. After the high point 55 of the drive cam 51 passes the uppermost point of its travel, the second lever 72 is lowered to its normal position.

In a sensing mode, the power means 80 is activated, retracting the latch 90. With the latch 90 retracted, the bellcrank 88 will be pivoted toward the end 63 of the second lever 72 by the coil spring 94, thus moving the fulcrum 89 into effective position over the end 63 of the second lever 72.

The constantly rotating camshaft 98 rotates the drive cam 51 clockwise; and the link 57 is driven upward, as the high point 55 of the drive cam 51 approaches the uppermost point of its travel, exerting an upward force on the second lever 72 pivotally connected thereto. The second lever 72 is restrained at one end 63 by the retractable fulcrum 89. The other end 74 is forced upward, exerting an upward force on the first lever

64 pivotally connected thereto.

The first lever is restrained at one end 61 by the coil spring 82. The other end 59 is free and moves upward, providing the record medium in the processing station 50 contains a code hole, pivoting about the second fulcrum 66 and carrying the sensing pin 56 into agreement with the perforation 71 in the backup 69 as the high point 55 of the drive cam 51 reaches the uppermost point of its travel. After the high point 55 of the drive cam 51 passes the uppermost point of its travel, the first 10 64 and second 72 levers are lowered to their normal positions.

If the record medium in the processing station 50 does not contain a code hole, the sensing pin 56 will be prevented from moving upward; and the other end 61 of the first lever 64 will be forced upward against the bias of the coil spring 82, and the 15 movably yieldable second fulcrum 66 activating the control means 68 as the high point 55 of the drive cam 51 reaches the uppermost point of its travel. After the high point 55 of the drive cam 51 passes the uppermost point of its travel, the first 64 and second 72 levers are lowered to their normal positions.

The constantly rotating cam shaft 98 also rotates the reset cam 96 clockwise. The high point 95 of this cam 96 lags the high point 55 of the drive cam 51 such that it reaches its uppermost point of travel after the high point 55 of the drive cam 51 has passed its uppermost point of travel. The action of the reset cam 96 pivots the tripodal lever 92 clockwise, causing the bellcrank reset stud 83 to pivot the bellcrank 88 clockwise, thus retracting the fulcrum 89 from its effective position relative to the end 63 of the second lever 72. The arm 91 of the tripodal lever 92 also supplements the action of the coil spring 87 in restoring the latch 90 to its normal position. By the time the high point 55 of the drive cam 51 reaches its lowermost point of travel, the high point 95 of the reset cam 96 has passed its effective position with respect to the tripodal lever 92; and the bellcrank 88 is once again in its normal position, held away from the end 63 of the second lever 72 by the retractable latch 90.

The function of the shackle 86 is to restrict the motion imparted to the second lever 72 by the drive cam 51 at the pivotal point of connection of the link 57 to the second lever 72 such that this point effectively reciprocates vertically.

We claim:

1. To a record media-processing apparatus having a processing station and comprising a supporting member, a first stop on said supporting member, a second stop on said supporting member, a lever normally resting on said first and said second stops, a processing tool carried by said lever adjacent said first stop, a first fulcrum on said processing tool, a second and normally retracted fulcrum on said supporting member spaced from said first fulcrum and movable to an effective position, said lever rockable on said first fulcrum when said second fulcrum is retracted and rockable on said second fulcrum when the latter is moved to effective position, a cyclically operable means operable to rock said lever, and power means to effect movement of said second fulcrum to effective position, wherein said lever has opposite free ends and said cyclically operable means is a cam operatively connected to said lever between said first and said second fulcrums, the addition of a shackle connecting said lever to said supporting member, said shackle operating between said point of connection of said cyclically operable means to said lever and a point 55 on said supporting member adjacent said second fulcrum.
